UNITED STATES PATENT OFFICE

94,343

DESIGN FOR A PROTECTIVE APRON

Otto Eidinger, Chicago, Ill., assignor to Robert Eidinger, doing business as Meer Made Products, Chicago, Ill.

Application October 3, 1934, Serial No. 53,470

Term of patent 3½ years

To all whom it may concern:

Be it known that I, Otto Eidinger, a citizen of Germany, residing at Chicago, in the county of Cook and State of Illinois, have invented a new, original, and ornamental Design for a Protective Apron, of which the following is a specification, reference being had to the accompanying drawing, forming a part thereof, in which,—

Fig. 1 is a front elevational view of an apron showing my design; and

Fig. 2 is a rear elevational view of the same.

I claim:

The ornamental design for a protective apron, substantially as shown.

OTTO EIDINGER.
